(57) **CLAIM**

I claim the ornamental design for a double-ended sports paddle, as shown and described.

DESCRIPTION

FIG. 1 is a perspective view of a double-ended sports paddle, showing my new design;

FIG. 2 is a front elevational view thereof;

FIG. 3 is a partial enlarged front elevational view thereof, taken along line 3 of FIG. 2;

FIG. 4 is a partial enlarged front elevational view thereof, taken along line 4 of FIG. 2;

FIG. 5 is a rear elevational view thereof;

FIG. 6 is a partial enlarged rear elevational view thereof, taken along line 6 of FIG. 5;

FIG. 7 is a partial enlarged rear elevational view thereof, taken along line 7 of FIG. 5;

FIG. 8 is a top plan view thereof;

FIG. 9 is a bottom plan view thereof;

FIG. 10 is an enlarged left-side elevational view of FIG. 1; and,

FIG. 11 is an enlarged right-side elevational view of FIG. 1.

1 Claim, 4 Drawing Sheets
